UNITED STATES PATENT OFFICE.

BENJAMIN WOOD, OF NEW YORK, N. Y., ASSIGNEE TO WOOD FLOONG COMPANY, OF NEW YORK, N. Y., A CORPORATION OF NEW YORK.

MATRIX-SCORCHER.

1,117,124.

Specification of Letters Patent. Patented Nov. 10, 1914.

Application filed July 2, 1913. Serial No. 777,060.

To all whom it may concern:

Be it known that I, BENJAMIN WOOD, a citizen of the United States, residing at New York, in the county of New York and 5 State of New York, have invented a new and useful Matrix-Scorcher, of which the following is a specification.

This invention relates to a matrix scorcher for drying a stereotype matrix in 10 curved form.

The device is used principally in connection with the so-called "dry process" of forming matrices, wherein the flog used in making the matrix contains a small percent- 15 age of moisture which, after the matrix has been molded, must be eliminated from the same.

In the old or wet process the sheet, together with the type upon which it is 20 pressed, is placed in a steam heated press and there remains until the type is thoroughly heated and the matrix becomes sufficiently dry to be removed from the type. In the "dry process" the sheet is immediately removed from the type after the impression has been made, and it is only necessary to dry out or scorch the slightly dampened sheet before placing the same in the stereotype mold. It is extremely desirable 25 in this dry process to have the scorching done when the matrix is substantially in the curved form as, if the matrix is scorched when flat and is thereafter curved, cracks in 30 its face are apt to develop.

The object of my invention is to improve 35 the construction of machines for thus drying the matrix sheets in curved form, to increase their efficiency, and to cheapen and simplify their manufacture.

With this object in view the invention 40 consists in certain devices, arrangements and combinations of parts which will be herein-after described and more particularly pointed out in the appended claims.

A preferred form of my invention is 45 shown in the drawings, in which—

Figure 1 is an end elevation of my device looking in the direction of the arrow 1 in Fig. 3; Fig. 2 is a vertical transverse section of the machine taken on the line 2—2 in Fig. 3; Fig. 3 is a side elevation of the device shown in Fig. 1 but showing the cover in closed position; and Fig. 4 is a detail sectional view showing the manner

of securing certain of the parts to the end 55 castings.

The machine illustrated in the drawings comprises essentially a curved supporting plate 10 rigidly secured to a pair of substantially semi-circular end castings 11 and 12. Secured to the plate 10 as by hinges 13, is a curved cover plate 14 provided with a handle 15 and so formed as to closely clamp the matrix plate upon the curved supporting plate 10 when in closed position. 65 The cover 14 is provided with a plurality of perforations 16 through which steam and moist air may escape from the matrix, which is designated by the reference letter A in Figs. 3 and 4.

Mounted within the supporting plate 10 and concentric therewith is a baffle plate 17 also provided with a plurality of perforations 18 and secured by screws 19 to flanges on the end castings 11 and 12 in spaced relation to the plate 10. Extending longitudinally through the machine and secured in lugs 20 in the end castings is a plurality of perforated burner tubes 21. As shown in Fig. 2 the two upper tubes are provided with a single longitudinal row of perforations, while the four lower and intermediate tubes are each provided with two rows of perforations, this arrangement resulting in a more even distribution of heat over the supporting plate. Each of the tubes 21 is provided with an air inlet or mixing device 22 and with a regulating valve 23. All of the tubes are connected by suitable fittings with a supply pipe 24 provided with a regulating valve 25.

The operation of the device will be evident from the preceding description, but a brief summary of the same may be of value. The operator upon receiving the matrix plate from the impression roller places the same upon the supporting plate 10 and closes the perforated cover thereon, thereby clamping the plate in curved position. The end castings are provided with 95 openings 26 through which the gas issuing from the various burner tubes may be easily ignited. The valves 23 serve to regulate the supply of gas to each tube and the valve 25 affords means by which the supply of fuel may be stopped without disturbing the adjustment of the several valves 23. The baffle plate 17 prevents the direct contact

of the jets issuing from the perforations in the tubes 21 with the supporting plate, and thus provides a more even distribution of the heat thereto.

5. I do not wish to be limited to the precise details disclosed herein as it is evident that various modifications may be made within the scope of my invention by those skilled in the art, but

10. What I do claim is:—

1. A matrix scorcher comprising a substantially semi-circular supporting plate, a curved clamping cover secured thereto, and a plurality of fuel burners mounted at substantially equal distances from the inner surface of said supporting plate, said burners having openings therein so proportioned in capacity as to provide substantially uniform heat distribution for said supporting plate.

2. A matrix scorcher comprising semi-circular end castings, a curved supporting plate secured thereto, a curved clamping cover hinged to said supporting plate, and

25 a. plurality of fuel burners extending through said castings and within said plate.

3. A matrix scorcher comprising a curved supporting plate, heating means for said

plate, and a curved perforated baffle plate concentric with said supporting plate and 30 acting to more evenly distribute heat thereto.

4. A matrix scorcher comprising end castings, a curved supporting plate secured thereto, flanges on said castings, a baffle plate secured to said flanges concentric with 35 said supporting plate but spaced therefrom, and heating means for said plates.

5. A matrix scorcher comprising semi-circular end castings, a curved supporting plate secured thereto, a perforated clamping 40 cover hinged to said plate, a perforated baffle plate secured to said end castings concentric with said supporting plate, and a plurality of burner tubes extending through said end castings and secured 45 therein, said tubes being provided with perforations arranged longitudinally thereof, and being all connected at one end with a single fuel supply pipe.

In testimony whereof I have hereunto set 50 my hand, in the presence of two subscribing witnesses.

BENJAMIN WOOD.
